(57) **CLAIM**

The ornamental design for a contact lens package as shown and described.

DESCRIPTION

FIG. 1 is a front, top, left perspective view of a contact lens package, showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, bottom, right perspective view thereof;

FIG. 9 is a perspective view showing the carrier of the contact lens package, in which the inner surface of the container is in a translucent mode when being exposed from air;

FIG. 10 is a perspective view showing the contact lens package when being rotated to move a bubble in the container, in which a portion of the inner surface of the container arranged in the bubble is in the translucent mode and another portion of the inner surface of the container arranged in the liquid is in the transparent mode; and,
FIG. 11 is a left side elevation view of FIG. 10.

The dashed broken lines in the drawing depict portions of the contact lens package that form no part of the claimed design.
